FIG. 1 is an isometric view of a platform for automobile body and frame repair system showing our new design with the platform being shown positioned above a floor;

FIG. 2 is a front view thereof, and the back view being essentially identical to the front view;

FIG. 3 is a side elevational view thereof, the two side views being essentially identical; and

FIG. 4 is an isometric view of the platform showing our new design installed in the floor with the top surface of the platform being essentially in a plane with the floor surface, which is shown in broken outline for illustrative purposes only.

We claim:

The ornamental design for a platform for automobile body and frame repair system, as shown and described.
